UNITED STATES PATENT OFFICE.

GEORGE EICHERT, OF CINCINNATI, OHIO.

SEWER-TRAP.

SPECIFICATION forming part of Letters Patent No. 250,511, dated December 6, 1881.

Application filed June 24, 1881. (No model.)

To all whom it may concern:

Be it known that I, GEORGE EICHERT, of Cincinnati, Hamilton county, Ohio, have invented a new and useful Improvement in Sewer-5 Traps, of which the following is a specification.

The object of my invention is a combined outlet and sewer-trap which is easily kept free, is gas-tight, and is accessible for inspection or repair from the interior of the basin.

10 In the accompanying drawings, Figure 1 is a vertical section of a portion of a sewer-catch-basin provided with my improvements. Fig. 2 represents the component members of my trap detached; Fig. 3, the lifting-rod with the 15 prongs.

A may represent any suitable sewer catch-basin having one or more inlets, B. A sink, C, in the basin-floor receives and supports by its flanged rim D the enlarged head or upper 20 portion, E, of discharge-pipe F. A pot, G, whose hooked hangers H rest in recesses of rim D, receives the lower end of the nozzle I, which constitutes the basin-outlet, whose collar J, constituting a part of the catch-basin 25 floor, also rests within the rim D, as shown. Standards K, which rise vertically from the inlet-mouth, guide and hold against lateral displacement a curb, L, that consists of a hollow cylinder open at bottom, and whose upper end terminates in a cage, M, having an orifice, m, to receive the lower extremity, n, of a rod, N, by which the said curb is made capable 30 of being lifted when desired. The engagement of rod N in orifice m is such as to permit the 35 rod to be rotated upon its own axis.

Projecting laterally outward and then downward from the rod N are two prongs, O, which follow the general contour of the curb, so as nearly to touch the same.

40 The pot G and outlet-nozzle I form collectively a stink-trap, that, while permitting the descent of the liquid contents of the basin, effect-

ually seals the sewer against the escape of its mephitic gases and vapors. The curb L, in its lower or normal position, (represented in Fig. 1,) 45 prevents for the time being the escape of solid débris, while its open cage-like upper portion permits the liquid and semi-liquid excreta or sewage to flow off and escape. Should the interstices of said cage become clogged with 50 trash, they may be rendered clear of such by rotating the pronged rod N O about its own axis. Finally, when it becomes desired to cleanse the basin after the removal of its more solid contents through the basin-mouth, water 55 is let into the basin, and the curb L M being suddenly elevated, the entire contents are permitted to escape.

The parts above described are so arranged and constructed as to be all easily accessible 60 and capable of inspection, repair, and replacement, without going outside of the basin.

The outlet F may be led off, either downward, as shown, or laterally, to suit the location in which the basin is used. 65

I claim as new and of my invention—

1. The combination of pendent pot G and outlet-nozzle I, below the level of the basin-floor and within the mouth of the discharge-pipe, with standards K, that rise from the basin-floor, and with the elevatable inclosing-curb L, substantially as set forth. 70

2. The combination, with standards K, that rise from the basin-floor in line with its discharge-nozzle, of the curb L M, whose lifting 75 handle or rod N is pivoted in the same and is armed with prongs O, as and for the purpose set forth.

In testimony of which invention I hereunto set my hand.

GEORGE EICHERT.
